UNITED STATES PATENT OFFICE.

JOHN W. HALEY, OF NORTH HARTLAND, VERMONT.

NUT-LOCK.

SPECIFICATION forming part of Letters Patent No. 292,301, dated January 22, 1884.

Application filed December 3, 1883. (Model.)

To all whom it may concern:

Be it known that I, JOHN W. HALEY, of North Hartland, in the county of Windsor and State of Vermont, have invented a new and 5 Improved Nut-Lock, of which the following is a full, clear, and exact description.

The invention consists in the combination, with a fish-plate having lugs on its outer surface, of a frame or check-nut, which frame is 10 provided with diagonally-opposite lugs, adapted to catch on the lugs on the fish-plate and prevent the locking-nut from turning.

Reference is to be had to the accompanying drawings, forming a part of this specification, 15 in which similar letters of reference indicate corresponding parts in all the figures.

Figure 1 is a longitudinal elevation of my improved nut-lock, showing it applied; Fig. 2, a cross-sectional elevation of the same and 20 of the rail and fish-plates. Fig. 3 is a perspective view of the check-nut or frame. Fig. 4 is a cross-sectional elevation of the fish-plate having the lugs.

The fish-plate A, against which the nut B rests, is provided with two hook-lugs, C C— 25 one to the left of the upper corner of the nut and the other to the right of the lower corner— of which hook lugs the lower one has a downwardly-projecting prong and the upper one an upwardly-projecting prong. A metal quad- 30 rilateral or other frame, D, fitting closely on the nut B, is provided at two diagonally-op- posite corners with two lugs, E, projecting in opposite directions, which lugs E fit in the 35 notches formed in the hook-lugs C. The nut B, which is secured on the bolt F, passed through the fish-plates A A' and the rail G, is drawn up tight; then the check-nut or frame

D is passed over the nut B, and then the nut is turned back or loosened until the lugs E 40 pass into the recesses or notches formed in the lugs C, thus preventing the nut from being unscrewed or loosened.

The nut-lock can be applied very easily, and in all cases prevents the nut from being 45 loosened.

The check-nut can move in the direction of its length in the recessed lugs, and thus allows for the contraction and expansion of the rail and fish-plate. 50

As the check-nut is held at diametrically- 55 opposite points, it will not rattle or jar off, as it would if held at one point only.

Having thus fully described my invention, I claim as new and desire to secure by Letters 55 Patent—

1. In a nut-lock, the combination, with a fish-plate having lugs C on its outer surface, of the frame or nut-check D, having lugs E at 60 opposite corners, the said lugs being adapted to catch on the lugs C, substantially as herein shown and described.

2. In a nut-lock, the combination, with the fish-plate A, having hook-lugs C, of the frame or nut-check D, having diagonally-opposite 65 lugs E, substantially as herein shown and de- scribed.

3. In a nut-lock, the frame or nut-check D, provided with lugs E at diagonally-opposite points, substantially as herein shown and de- 70 scribed.

JOHN W. HALEY.
